ICE CUBE TRAY

Alvin G. Sherman, Grosse Pointe, Mich.

Application August 9, 1937, Serial No. 158,123

11 Claims. (Cl. 62—108.5)

This invention relates to ice cube trays.

This invention has particularly to do with an ice tray which is formed of flexible rubber and supported at the outside and between individual 5 ice cube pockets by a reinforcing frame.

An object of the invention is to provide an ice tray so designed that individual ice cubes may be easily removed therefrom. This is accomplished, first, by suspending each individual soft rubber 10 ice pocket from a reinforcing frame which is definitely larger in transverse dimensions than the dimensions of the cross-section of the ice pocket or the ice cube to be formed therein; and, secondly, by an unusual bottom design in the ice 15 pocket which quickly releases the cube from the bottom wall.

Upward pressure on the rubber ice pocket and ice cube contained therein will result in an easy removal of the ice cube since the soft rubber walls 20 will readily strip from the ice cube. Each ice pocket will essentially turn inside out until the ice cube is fully released. The bottom wall of the ice cube is designed to have a substantially circular depression therein of smaller diameter than 25 the width of the wall. During the removal of the ice cube this depression will be subjected to pressure and will gradually fold inwardly, to form a sort of dome in the bottom of the ice pocket meanwhile stripping itself from the bottom 30 of the ice cube and readily releasing the bottom wall of the ice pocket.

A further object of the invention is to furnish an ice pocket that is especially adapted for use with a continuous ice cube forming and dispensing 35 device such as that disclosed in my Patent No. 1,857,122.

In the drawings:

Fig. 1 is a cut away perspective view of an ice tray assembly showing the relation of the reinforcing wire frame to the soft rubber tray.

Fig. 2 illustrates the supporting frame of the tray.

Fig. 3 is a side view of the assembled tray.

Fig. 4 is a transverse section of the assembly.

Fig. 5 is a transverse section showing a modified self-leveling construction.

Fig. 6 is a longitudinal section of the assembly.

Fig. 7 is a detail cross-section of an ice pocket and ice cube illustrating the manner in which 50 the walls of the pocket strip from the ice cube.

Fig. 8 is a view similar to Fig. 7 in which the side walls and bottom of the ice pocket are completely freed from the ice cube.

Fig. 9 is an enlarged view of a section of the 55 assembly showing the dimensional relationship

between the ice pocket and the individual supporting means.

Fig. 10 illustrates a modification of the invention as adapted to a continuous ice forming machine.

Fig. 11 is a detailed cross-sectional view of the modification of Fig. 10 taken on the lines 11—11.

Fig. 12 is a side view showing the conveyor chain.

Figs. 13, 14 and 15 illustrate various stages 10 in the stripping of the ice cube from the walls and bottom of the ice pocket.

A preferred embodiment of one modification of the invention is illustrated in Figs. 1 to 9. The reinforcing means consists of a frame 1 (Fig. 2) 15 composed of support members 2, a top edging bar 3, and cross-members 4 and 5, all suitably soldered or welded together. A soft rubber tray 6 (Fig. 1) is formed on frame 1 in such manner that the edging bar 3 and the cross-members 4 20 and 5 are enveloped directly within the rubber itself. Individual ice cube pockets 7 are formed in each of the openings between the cross-members 4 and 5. In the bottom wall of each of the pockets a depression 8 is formed. This depression is preferably, though not necessarily, substantially circular in contour, and smaller in diameter than the width of the bottom of the ice pocket.

An important feature of the invention is the 30 manner in which the side walls of each of the ice pockets are designed in relation to the cross-members 4 and 5 and the edging bar 3. At the normal level of the water in the ice pocket it is important that there be an upward and outward 35 extending surface or arcuate brim 9 on each side wall. Referring to Fig. 4, for example, it will be seen that, between the edge of a formed ice cube and the reinforcing means of the supporting frame, as, for example, members 3 and 4, 40 there is a brim space designated "a", and this is true on each side of the cube as shown by the longitudinal cross-section in Fig. 6. The walls of the ice pockets 7 are preferably tapered slightly toward the bottom though this is not necessary 45 to the successful operation of the device. In addition it is preferable that the side walls of the pocket be formed of very thin flexible material. This will facilitate the removal of the frozen substance as well as shorten the freezing time. 50

In Fig. 5 the cross-members 4 are shown dropped slightly from the edging bar 3 to form a self-leveling construction which facilitates the filling of the ice pockets with water.

In the operation: When the completely formed 55

- ice cube is subjected to upward pressure applied directly to the bottom of the flexible rubber pocket, there will be a tendency for the walls of the ice pocket to move upward with the ice cube.
- 5 These walls will be held down at the top by the supporting cross-members 4 and 5, and the result will be that the upper, outwardly extending brim portion 9 of the walls will tend to pivot about the reinforcing members 3, 4 and 5 as fulcrums.
- 10 This tendency to pivot will be transformed into a peeling action, best shown in Fig. 7, whereby the flexible walls of the ice pocket will be turned inside out and the ice cube will be easily freed from the pocket.
- 15 In the modification shown in Figs. 11 to 15, the ice pockets are formed in the longitudinal groups of as many as are desired. Parallel conveyor chains formed of links 10 are connected by transverse bars 12. The flexible rubber ice pockets 20 are reinforced by apertured frames of substantially rigid material. Side members 13 of said frame are shown (end view) in Figs. 13, 14 and 15. Outwardly extending bearing lugs 14 are provided on the side members 13 for engaging 25 the transverse bars 12 of the chain conveyor. These bearing lugs 14 are alternately spaced on each side of the frame to avoid interference with lugs of adjacent frames when they are suspended on the bars 12, as shown particularly in Fig. 10.
- 30 The side members 13 are joined at each end, and between each ice pocket, by cross-members 15 shown in cross-section in Fig. 11.

The flexible rubber ice pockets 16 formed around the frame bars 13 and 15 are provided 35 with a reinforced bottom flange 17 in which is embedded a square apertured reinforcing member 18 which extends substantially to the edges of the flange 17. In the rubber bottom of the pockets is formed a semi-spherical depression 19 40 which extends through the aperture in the reinforcing member 18.

The operation of the above described modification is somewhat different from that of the first described device. The distance *a* is still provided between the reinforcing frame members 13 45 and 15 and the upper edges of the ice cube so that the side walls, as previously described, will function around the frame members 13 and 15 and strip or peel from the ice cube when the ice 50 pocket is subjected to upward pressure. When the flanges 17 strike the lug bearings 14 the lower portion of the ice pocket is no longer free to rise. The side walls of the pocket are, however, flexible enough that they will stretch to allow 55 the peeling action to continue. Furthermore, the pressure will be exerted directly on the ice cube through the portion 19 of the bottom of the ice pocket. The peculiar formation of the bottom of the ice cube, due to this depression portion 19, 60 will result in a peeling of the bottom away from the ice cube as pressure is exerted upwardly through the aperture in the reinforcing member 17 (Fig. 15). In this manner the entire cube 65 can be freed from the rubber pocket by a shorter stroke than was necessary in the first modification described.

This modification illustrated in Figs. 11 to 15 is especially adapted for use with continuous ice forming machines of the endless conveyor type, 70 as described, for example, in my Patent No. 1,857,-122. In these machines a special ejector member is provided with teeth or projections adapted to cooperate with the rubber portions 19 in the bottom of the ice pocket.

75 It will further be seen that a wire reinforcing

frame is not necessary to the invention as long as there is present an equivalent thereof such as, for example, a stiff rubber bridging member between the ice pockets.

What I claim is:

1. A container suitable for liquids to be solidified, comprising a plurality of individual pockets having flexible side walls, a flexible brim portion on each of said pockets extending outward from said side walls, relatively stiff bridging means 10 between each of said pockets and extending around the edge of said brim, said bridging means being adapted to serve as a hold down for the outer edge of said brim portion when a pocket containing the solidified substance is subjected 15 to movement relative to said bridging means whereby said side walls will peel from said solidified substance, and a substantially flat bottom in each of said pockets having a depression 20 formed therein which is adapted to turn inside out during the removal of said substance from said pockets.

2. In a rubber tray suitable for liquids to be solidified, a substantially rigid frame comprising an outer rim, and spaced cross-members extending 25 across said outer rim in two directions to form regular enclosed spaces therebetween, and a tray member formed on said frame comprising a number of spaced individual pockets having relatively thin flexible side walls and arranged 30 to register with said enclosed spaces in said frame, and flexible bridging portions integral with and between the adjacent walls of the pockets and reinforced by the cross-members of said frame, the upper portion of said flexible walls 35 being formed such that pressure against the bottom of any individual pocket when filled with a solidified substance will peel the flexible side walls outward and downward from point of contact with said solidified substance.

3. A tray suitable for containing substances to be solidified comprising a skeleton wire frame embedded in a soft rubber body made up of individual ice pockets and rubber bridging portions therebetween, cross-members on said frame positioned between and around said pockets and embedded in said bridging portions, and an outwardly extending flexible brim portion on each of said pockets integrally connected with said bridging portions and frame such that a solidified substance when contained in said pockets and subjected to pressure through the bottom of said pockets will be freed from said pocket by reason of the pocket stripping away from said substance.

4. In a rubber ice forming pocket, a substantially rigid frame, an ice pocket formed on and supported in said frame comprising relatively thin flexible side walls having an outwardly extending brim portion in which is embedded the frame, a flexible bottom portion enclosing said side walls and provided with an outwardly extending abutment means, a reinforcing member in said abutment means, and means on said frame for engaging and blocking the movement of said abutment means as it is moved toward said frame, said frame being adapted to serve as a pivot about which the brim portion of said side walls turns when the ice filled pocket is moved toward the frame.

5. In a rubber ice forming pocket, an enclosed substantially rigid frame, an ice pocket formed on and supported in said enclosed frame comprising relatively thin flexible side walls having an outwardly extending brim portion in which is embedded the frame, a flexible bottom portion 70

- enclosing said side walls and provided with an outwardly extending substantially rigid flange, and means on said frame for engaging and blocking the movement of said flange as it is moved 5 toward said frame, said frame being adapted to serve as a pivot about which the brim portion of said side walls turns when the ice filled pocket is pressed toward the frame.
6. In a soft rubber ice tray, a substantially thin rigid frame and cross-members, spaced ice pockets comprising relatively thin resilient side walls having outwardly extending brim portions supported on said cross-members, a flexible bottom portion enclosing said side walls and provided 10 with an outwardly extending substantially rigid flange, a substantially semi-spherical depressed portion in said flexible bottom portion, and abutment means on said frame for engaging and blocking the movement of said flange when it is pushed 15 toward said frame, said depressed portion and said brim portions being so designed that pressure on said bottom portion toward said frame will tend to peel the side walls of the pocket from ice contained therein, until said flange strikes the abutment means on the frame, and continued 20 pressure on said depressed portion toward said frame will peel the remaining walls and bottom of the pocket from said ice.
7. In a soft rubber ice tray, a substantially thin rigid frame and cross-members, spaced ice pockets formed on and supported in said frame, each pocket comprising relatively thin resilient side walls having outwardly extending brim portions in which are embedded the cross-members of the frame, a flexible bottom portion enclosing said side walls and provided with an outwardly extending substantially rigid flange, a substantially semi-spherical depressed portion in said flexible bottom portion, and abutment means on said 25 frame for engaging and blocking the movement of said flange when it is pushed toward said frame, said depressed portion and said brim portions being so designed that pressure on said bottom portion toward said frame will tend to peel the side walls of the pocket from ice contained therein, until said flange strikes the abutment means on the frame, and continued pressure on said depressed portion toward said frame will peel the remaining walls and bottom of the pocket from said ice.
8. In a soft rubber ice tray, a substantially thin rigid frame and cross-members, spaced ice pockets formed on and supported in said frame, each pocket being surrounded at its top portion by cross-members of said frame and comprising relatively thin resilient side walls having outwardly extending brim portions supported by said cross-members, a flexible bottom portion enclosing said side walls and provided with an outwardly extending abutment means, a substantially semi-spherical depressed portion in said flexible bottom portion, and means on said frame for engaging and blocking the movement of said abutment means when it is pushed toward 50 said frame, said depressed portion and said brim portions being so designed that pressure on said bottom portion toward said frame will tend to 55 peel the side walls of the pocket from ice contained therein, until said flange strikes the abutment means on the frame, and continued pressure on said depressed portion toward said frame will peel the remaining walls and bottom of the pocket from said ice.
9. In a soft rubber ice tray, a substantially thin rigid frame and cross-members, spaced ice pockets formed on and supported in said frame, each pocket being surrounded at its top portion by cross-members of said frame and comprising relatively thin resilient side walls having outwardly extending brim portions in which are embedded the cross-members of the frame, a flexible bottom portion enclosing said side walls and provided with an outwardly extending substantially rigid flange, a substantially semi-spherical depressed portion in said flexible bottom portion, and means on said frame for engaging and blocking the movement of said flange when it is pushed toward said frame, said depressed portion and said brim portions being so designed that pressure on said bottom portion toward said frame will tend to peel the side walls of the pocket from ice contained therein, until said flange strikes the abutment means on the frame, and continued pressure on said depressed portion toward said frame will peel the remaining walls and bottom of the pocket from said ice.
10. An ice tray for use with a continuous conveyor ice forming unit comprising a series of connected ice pockets formed in soft rubber, a substantially rigid supporting frame surrounding each of said ice pockets, an outwardly extending flexible brim portion on each of said pockets connecting the same with said frame, and means on said frame for supporting said tray in a continuous conveyor, said ice pockets being adapted to be released from ice cubes formed therein by movement toward said frame whereby the pockets are turned partially inside out and peeled from the ice cube.
11. An ice tray for use with a continuous conveyor ice forming unit comprising a series of connected ice pockets formed in soft rubber, a substantially rigid supporting frame surrounding each of said ice pockets, each pocket comprising relatively thin flexible side walls, an outwardly extending brim portion on said side walls connecting them to said frame, a flexible bottom portion enclosing said side walls, and abutment means extending outwardly from said side walls at a point near the bottom of the pocket, means on said frame for supporting said tray in a continuous conveyor, and means on said frame for engaging and blocking the movement of said abutment means on the pockets as the same are pushed toward said frame, said frame being adapted to serve as a hold down for the outer edge of the brim portion of said side wall when bottoms of the pockets containing ice cubes formed therein are forced toward said frame, whereby the sides and bottom of the pocket are freed from said ice cubes upon continued application of force through said bottom portion toward said frame.

ALVIN G. SHERMAN.
